UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

BELT-TIGHTENER.

No. 905,526.

Specification of Letters Patent.

Patented Dec. 1, 1908.

Application filed June 2, 1908. Serial No. 436,203.

To all whom it may concern:

Be it known that I, BENGT M. W. HANSON, a citizen of the United States, residing at Hartford, in the county of Hartford and

5 State of Connecticut, have invented certain new and useful Improvements in Belt-Tighteners, of which the following is a specification.

This invention relates to belt-tighteners 10 the object of the invention being to provide a simple article of this character, for applying the tension necessary to a driving-belt to remove slack therefrom.

The device may be used with advantage 15 in many different connections although it is of particular utility when employed in conjunction with or as part of an organized grinding or similar metal-working machine where its compact form, simplicity and effectiveness are desirable attributes.

In the drawings accompanying and forming part of this specification I illustrate in detail one convenient form of embodiment of the invention which to enable those skilled 25 in the art to practice the same will be set forth at length in the following description, while the novelty of the invention will be included in the claims succeeding said description. From the statement just made it 30 will be obvious that I do not restrict myself to the showing made by said description and drawings for certain variations may be adopted within the scope of my claims.

Referring to said drawings, Figure 1 is a 35 top, plan view of a belt-shifter including my invention and showing also the slide of a grinding machine on which said belt shifter is mounted, and, Fig. 2 is a side elevation of the parts illustrated in the preceding figure, 40 the belt for sake of clearness being omitted in the first-mentioned figure.

Like characters refer to like parts in both figures.

In the drawings the numeral 5 represents 45 a slide which is common in certain classes of grinding and analogous machines and which constitutes the base or bed of framing which sustains the belt-tightening mechanism and adjunctive devices. From one end 50 or it may be a side of said slide, a pair of standards as 6 is shown as rising, said standards terminating at their upper ends in elongated bearings or hubs as 7 which receive for rotary motion a primary shaft as

55 8. Said shaft is a primary one so far as the

tool-shaft or spindle, hereinafter described, is concerned. Upon one end of said shaft 8 there may be fastened a driver as 9 represented as consisting of a pulley.

The slide 5 at the end or side thereof opposite that equipped with the standards 6, has two bearings as 10 which support for rotary motion a shaft as 11 which in a machine such as that to which allusion has been made, constitutes the tool-spindle. Said 60 shaft 11 is shown as provided with a tool as 12 at one end thereof in the form of the well known grinding-disk. The shaft or tool-spindle 11 has suitably fastened thereto between its ends and between the bearings a 70 driven member as 13 which is represented as consisting of a peripherally grooved pulley.

The primary or main shaft 8 is shown as provided with a driving member as 14, fastened thereto in any desirable way and located 75 between the hubs or bearings 7. The driving member 14 also consists of a pulley; it is shown as being peripherally plain and as of greater diameter than the pulley 13 by virtue of which latter fact the tool can be 80 driven at a high speed.

The belt-tightener involves in its make-up preferably an oscillatory arm or rocker and one such as that denoted in a general way by 15 subserve satisfactorily my purpose. 85 The rocker or oscillatory arm is illustrated as being substantially flat and as composed of two relatively-elongated, side branches disposed in parallelism and a cross-piece 16 connecting said side arms, and I may inexpensively and strongly produce said rocker by casting. The parallel side branches of the rocker 15 support at their forward or inner ends a shaft as 17 which carries a rotary idler or belt-tightening pulley as 18 90 under which the upper run of a belt as 19 is shown as passing, the ends of the belt being looped around the pulleys 13 and 14 the latter of which is located between the side branches of the rocker or arm 15. The 95 shaft 17 as well as the cross-piece 16 serves as a transverse strut or brace for the rocker 15. The rear or outer ends of the rocker 15 are shown as pivoted as at 20 to lugs 21 on the hubs or bearings 7, the lugs or ears 21 100 extending inwardly or forwardly. The outer end of the rocker 15 is shown as pivoted between these lugs to further strengthen the structure.

I do not rely upon gravity or the weight 110

of the rocker 15 to apply the necessary stress to the idle run of the belt 19 to eliminate slack therein, but, as will hereinafter appear, provide positive means for this purpose. I use the term "idle" as applied to the upper run of the belt to distinguish it from the lower or working run thereof, said lower run doing the major part of the power-transmitting operation. By having the take-up pulley act against the idle run, the working run is not interfered with and I can therefore obtain from the working run the maximum draft or pulling effect and this without loading the working run.

On one of the side branches of the rocker 15 or that shown in the foreground in Fig. 2 I may form a lug or ear as 23 illustrated as being in the plane of the body of said rocker and I have illustrated as tapped through this lug from above an adjusting or thumb-screw as 24 to which is shown as connected the upper end of a pull spring as 25, the lower end of said spring being suitably connected with the slide 5. Said spring exerts a constant downward pull on the rocker 15 to thoroughly remove slack in the belt 19. The tension of the spring can be readily regulated by the screw 24. One of the branches of the rocker 15 (or if necessary both of said branches) may be provided with a toe as 26 constituting a con-

venient stop and which when the belt 19 is removed abuts against an adjacent standard 6 on the descent of the rocker 15 to prevent the pulley 18 moving all the way to the slide 5 at such time.

Having described the invention, what I claim is:

1. The combination of a pair of pulleys, a substantially flat rocker having connected side branches between which one of said pulleys is received at one end of said rocker, and an idler pulley rotatively supported at the other end of said rocker and co-operative with the first mentioned pulleys. 40

2. The combination of a rotary belt pulley, a standard supporting said pulley, a substantially flat rocker comprising side branches and a bar connecting said branches between their ends, one end of each of said side branches being pivoted to the standard at opposite sides of said pulley to receive said pulley between said branches, and an idler pulley rotatively supported by and between said branches at their opposite ends. 45

In testimony whereof I affix my signature in presence of two witnesses.

BENGT M. W. HANSON.
